UNITED STATES PATENT OFFICE

2,208,131

REFLECTOR

Morris Kaplowitz, Brooklyn, N. Y., assignor to
 Microphone Corporation of America, Brooklyn,
 N. Y., a corporation of New York

Original application February 20, 1936, Serial No.
 64,871. Divided and this application March 7,
 1939, Serial No. 260,459

7 Claims. (CL 88—82)

This application is a divisional application, having been divided out from pending application filed February 20, 1936, Serial No. 64,871 on which Patent No. 2,155,092 was issued April 18,

5 1939.

This invention relates to reflectors of the type adapted to be mounted on vehicles in order to reflect light from the headlight of a following vehicle back to the driver of the latter, and one object thereof is the provision of certain useful improvements in reflectors of the multiple type. Such reflectors may also be mounted on stationary supports, as, for instance, at curves in highways and at dead ends of streets. The casings 10 of the reflectors may be molded, cast, or otherwise formed in the shape of letters, numerals, figures, trade-marks, designs, etc.

A further object of the invention is the provision of such a reflector with means for varying the distance between the lens and its mirror. This adjustment means is necessary so as to accommodate graded groups of lenses with various focal lengths and still maintain a reflector of very high optical efficiency. These variations are 15 due to physical or optical variations and are common in the manufacture of inexpensive lenses. It is further useful as the means of controlling the optical characteristics of the reflector by controlling the angle of the returning rays so as 20 to meet specific optical requirements of various specifications.

A still further object of the invention is to provide such a reflex reflector with a multiple casing having hermetically sealed units which 25 can be manufactured very inexpensively in various shapes, forms, and of various materials.

Another object of this invention is to provide a reflector having a high degree of optical efficiency and at the same time having its cost of manufacture reduced to a minimum.

The above and other objects will be made apparent in the description below, in which characters of reference refer to like-named parts in the accompanying drawing, forming a part 40 thereof.

Referring briefly to the drawing:

Figure 1 is a plan view of an assembled multiple reflector.

Figure 2 is a side view of Figure 1.

Figure 3 is a cross-sectional view taken on the line 3—3 of Figure 1.

Referring in detail to the drawing, the numeral 10 represents the face plate of a casing 41 provided with a peripheral flange 11. At spaced-apart positions, a number of identical tubular

walls 12 project inward from the front wall 10, that portion of the face 10 which would come within the enclosure of each wall 12 being blanked out in the casting or stamping of the casing. Each wall 12 encloses a socket 13 having a rounded base 14 from which the cylindrical wall 15, of the same diameter as the base 14, extends upwardly. A peripheral shoulder 16 marks the division between the inner surface of the wall 12 and the wall 15. The entire casing, together with the various features of the sockets 13, as above set forth, may be cast, stamped out, or otherwise formed of unitary construction.

A reflector element or mirror 17 having the back 18 whose concave surface is covered with a suitable coating of material such as chromium plate, is provided with a cylindrical flange 19 which is adapted to fit very snugly within the wall 15, so that it may be forced into position at a predetermined distance from the seat 16. A glass sphere or lens 20 of any suitable color is mounted on the seat formed by the shoulder 16. A soft rubber ring or gasket 44 is placed about the equatorial belt of the sphere 20 to serve as a water-proofing packing to prevent moisture from getting below the lens. After the mirror 17, the lens 20, and the gasket 44 have been mounted in the socket 13, a plate 45, having a plurality of circular openings therein with each of these openings surrounded by an upwardly and inwardly projecting frusto-conical lip 46, is set down against the front face 42 of the wall 10, with each lip 46 surrounding one of the lenses 20. A peripheral flange 43 surrounds the face 42, and this flange is then turned inward against the periphery of the plate 45, as shown at 47, to lock the plate 45 against the casing 41. Other forms of lenses aside from spheres may be used with equal advantage.

No means for attaching the reflector on a vehicle or other support has been shown or described, as such means does not form any part of the present invention; obviously, any suitable means may be provided. It is also obvious that modifications in form and structure may be made without departing from the spirit and scope of the invention.

I claim:

1. A multiple reflector having a housing consisting of front and rear walls, the front face of said rear wall having a plurality of openings therein, said openings having peripheral walls extending substantially perpendicular to said front face and forming peripherally walled sockets, said peripherally walled sockets being integral with

5 said rear wall, said front wall having openings therethrough, said openings being in alignment with said sockets in said rear wall, separate reflector cups having concave mirrored bottoms mounted one in each of said sockets, said concave mirrored bottoms facing in the same direction as said front face of said rear wall, means to retain said reflector cups in said sockets, a lens mounted in each of said openings in said front wall, said lenses being larger in diameter than said openings in said front wall, the front faces of said lenses projecting through said openings, said front face of said rear wall being positioned over the back faces of said lenses, the back faces 10 of said lenses entering said sockets and facing said concave mirrored bottoms of said reflector cups, said lenses being positioned between the inner peripheries of said openings in said front wall and the open ends of said sockets, said open 15 ends of said sockets forming seats for said lenses, the outer circumferences of the back faces of said lenses being seated on said seats, means for varying the distance between said lenses and said concave mirrored bottoms of said reflector cups to 20 bring said lenses and said bottoms into substantially focused relation, said front wall pressing said lenses against said seats, and means for locking said front and rear walls together and simultaneously locking said lenses and said reflector cups into said sockets.

25

30

30 reflector cups into said sockets.

35 2. A multiple reflector having a housing consisting of front and rear walls, the front face of said rear wall having a plurality of openings therein, said openings having peripheral walls extending substantially perpendicular to said front face and forming peripherally walled sockets, said peripherally walled sockets being integral with said rear wall, said front wall having openings therethrough, said openings being in alignment with said sockets in said rear wall, separate reflector cups having concave mirrored bottoms mounted one in each of said sockets, said concave mirrored bottoms facing in the same direction as said front face of said rear wall, said reflector cups being slidably retained by said peripheral walls of said sockets, a lens mounted in each of said openings in said front wall, said lenses being larger in diameter than said openings in said front wall, the front faces of said lenses projecting through said openings, said front face of said rear wall being positioned over the back faces of said lenses, said back faces of said lenses entering said sockets and facing said concave mirrored bottoms of said reflector cups, said lenses being positioned between the inner peripheries of said openings in said front wall and the open ends of said sockets, said open ends of said sockets forming seats for said lenses, the outer circumferences of the back faces of said lenses being seated on said seats, the slidable relation between said peripheral walls of said sockets and said reflector cups providing means for varying the focal distance between said lenses and said reflector cups for adjusting said lenses and said reflector cups into a substantially focused relation, said front wall pressing said lenses against said seats, and means for locking said front and rear walls together and simultaneously locking said lenses and said reflector cups into said sockets.

70

70 said sockets.

3. A multiple reflector having a housing consisting of front and rear walls, the front face of said rear wall having a plurality of openings therein, said openings having peripheral walls 75 extending substantially perpendicular to said

front face and forming peripherally walled sockets, said peripherally walled sockets being integral with said rear wall, said front wall having openings therethrough, said openings being in alignment with said sockets in said rear wall, 5 separate reflector cups having concave mirrored bottoms mounted one in each of said sockets, said concave mirrored bottoms facing in the same direction as said front face of said rear wall, said reflector cups being slidably retained by said peripheral walls of said sockets, a lens mounted 10 in each of said openings in said front wall, said lenses being larger in diameter than said openings in said front wall, the front faces of said lenses projecting through said openings, said front face of said rear wall being positioned over 15 the back faces of said lenses, said back faces of said lenses entering said sockets and facing said concave mirrored bottoms of said reflector cups, said lenses being positioned between the inner 20 peripheries of said openings in said front wall and the open ends of said sockets, seats of relatively soft material, said seats surrounding the open ends of said sockets, the outer circumferences of the back faces of said lenses being seated 25 on said seats, the slidable relation between said peripheral walls of said sockets and said reflector cups providing means for varying the focal distances between said lenses and said reflector 30 cups for adjusting said lenses and said reflector cups into a substantially focused relation, said front wall pressing said lenses against said seats, and means for locking said front and rear walls together and simultaneously locking said lenses and said reflector cups into said sockets. 35

4. A multiple reflector having a housing consisting of front and rear walls, the front face of said rear wall having a plurality of openings therein, said openings having peripheral walls extending substantially perpendicular to said front face and forming peripherally walled sockets, said peripherally walled sockets being integral with said rear wall, said front wall having openings therethrough, said openings being in alignment with said sockets in said rear wall, separate reflector cups having concave mirrored bottoms mounted one in each of said sockets, said concave mirrored bottoms of said cups facing in the same direction as said front face of said rear wall, means to retain said reflector cups in said sockets, a lens mounted in each of said openings in said front wall, said lenses being larger in diameter than said openings in said front wall, the front faces of said lenses projecting through said openings, said front face of said rear wall being positioned over the back faces of said lenses, said back faces of said lenses entering said sockets and facing said concave mirrored bottoms of said reflector cups, said lenses being positioned between the inner peripheries of said openings in said front wall and the open ends of said sockets, seats of relatively soft material, said seats surrounding the open ends of said sockets, the outer circumferences of the back faces of said lenses being seated on said seats, means to adjust the space between said lenses and said concave mirrored bottoms of said reflector cups to bring said lenses and bottoms into substantially focused relation, said front wall pressing said lenses against said seats, and means for locking said front and rear walls together and simultaneously locking said lenses and said reflector cups into said sockets.

5. A multiple reflector having a housing consisting of front and rear walls, the front face of

- 5 said rear wall having a plurality of openings therein, said openings having peripheral walls extending substantially perpendicular to said front face and forming peripherally walled sockets, said peripherally walled sockets being integral with said rear wall, said front wall having openings therethrough, said openings being in alignment with said sockets, separate reflector cups having concave mirrored bottoms mounted 10 one in each of said sockets, said concave mirrored bottoms facing in the same direction as said front face of said rear wall, means to retain said reflector cups in said sockets, a lens mounted in each of said openings in said front wall, said lenses being larger in diameter than said openings in said front wall, the front faces of said lenses projecting through said openings, said front face of said rear wall being positioned over the back faces of said lenses, said back faces of said lenses entering said sockets and facing said concave mirrored bottoms of said reflector cups, said lenses being positioned between the inner peripheries of said openings in said front wall and the open ends of said sockets, said open ends of said sockets forming seats for said lenses, the outer circumferences of the back faces of said lenses 15 being seated on said seats, the slidible relation between said peripheral walls of said sockets and said reflector cups providing means for varying the focal distance between said lenses and said reflector cups for adjusting said lenses and said reflector cups into a substantially focused relation, said front wall pressing said lenses against said seats, and means for locking said front wall and rear wall together, and simultaneously locking said lenses and said reflector cups into said 20 sockets. 25
7. A multiple reflector having a housing consisting of front and rear walls, the front face of said rear wall having a plurality of openings therein, said openings having peripheral walls 30 extending substantially perpendicular to said front face and forming peripherally walled sockets, said peripherally walled sockets being integral with said rear wall, said front wall having openings therethrough, said openings being in alignment with said sockets, an auto-collimating catadioptric reflecting unit mounted in each of said peripherally walled sockets, the front faces of said units projecting from said sockets through said front face of said rear wall, 35 said peripherally walled sockets forming retaining casings for said units, said front wall being placed over said units projecting from said rear wall, said units projecting through said openings in said front wall, said units being larger in diameter than said openings in said front wall, said front wall pressing said units into said sockets, said rear wall having a surrounding annular rim, said front wall nesting within said rim, said rim extending above said front wall 40 and being peened inwardly over said front wall to engage said front wall and lock said front and rear walls together and thereby simultaneously locking said lenses and said reflector cups in said sockets. 45
- 40 6. A multiple reflector having a housing consisting of front and rear walls, the front face of said rear wall having a plurality of openings therein, said openings having peripheral walls extending substantially perpendicular to said front face and forming peripherally walled sockets, said peripherally walled sockets being integral with said rear wall, said front wall having openings therethrough, said openings being in alignment with said sockets, separate reflector 45 cups having concave mirrored bottoms mounted one in each of said sockets, said concave mirrored bottoms facing in the same direction as said front face of said rear wall, said reflector cups being slidably retained by said peripheral walls 50 of said sockets, each of said openings of said front wall having an upwardly and inwardly pro-
